UNITED STATES PATENT OFFICE

153,918

DESIGN FOR A COMB HOLDER OR THE LIKE

Milton W. Bernstein, Leominster, Mass., assignor, by mesne assignments, to Foster Grant Co., Inc.,
Leominster, Mass., a corporation of Massachusetts

Application December 24, 1947, Serial No. 143,316

Term of patent 14 years

(Cl. D86—10)

To all whom it may concern:

Be it known that I, Milton W. Bernstein, a citizen of the United States, residing at Leominster, in the county of Worcester, State of Massachusetts, have invented a new, original, and ornamental Design for a Comb Holder or the like, of which the following is a specification, reference being had to the accompanying drawings, forming part thereof, in which:

Figure 1 is a front view of a comb holder, embodying my design;

Fig. 2 is a side view thereof;

Fig. 3 is a top plan view, and

Fig. 4 is a perspective view of the comb holder.

I claim:

The ornamental design for a comb holder or the like, substantially as shown.

MILTON W. BERNSTEIN.
